Primary Examiner — Ian Simmons*Assistant Examiner* — Keith Frank(74) *Attorney, Agent, or Firm* — Clayton, McKay & Bailey, PC(57) **CLAIM**

The ornamental design for a torso trainer, as shown and described.

DESCRIPTION

FIG. 1 is a perspective view of a torso trainer showing applicant's new design.

FIG. 2 is a front view of the torso trainer.

FIG. 3 is a rear view of the torso trainer.

FIG. 4 is a left-side view of the torso trainer.

FIG. 5 is a right-side view of the torso trainer.

FIG. 6 is a top view of the torso trainer; and,

FIG. 7 is a bottom view of the torso trainer.

The broken lines depict portions of the torso trainer and form no part of the claimed design.
